UNITED STATES PATENT OFFICE.

**JOHN BEISWANGER, OF STEUBENVILLE, OHIO, ASSIGNOR TO GILL BROTHERS COMPANY,
OF STEUBENVILLE, OHIO, A CORPORATION OF WEST VIRGINIA.**

DESIGN FOR A SHADE-BOWL.

52,003.

Specification for Design.

Patented May 7, 1918.

Application filed February 1, 1918. Serial No. 215,008. Term of patent 7 years.

To all whom it may concern:

Be it known that I, JOHN BEISWANGER, a citizen of the United States of America, and resident of Steubenville, county of Jefferson, State of Ohio, have invented a certain new, original, and ornamental Design for a Shade-Bowl, of which the following is a specification.

In the accompanying drawing I have illustrated a shade bowl embodying my invention. The figure is a perspective view taken from the side and slightly below the center of the article.

The device as shown consists of a lower convex portion 1 and an upper meridianally concave portion 2, both of circular or substantially circular cross-section, meeting in a horizontal circular edge or surface 3. The

upper or concave surface is molded in the form of Doric flutes 4 and the lower portion is formed with meridianally extending depressions or flutes 5, some of which are ornamented with conventionalized figures 6 in the nature of an inverted fleur-de-lis. Reference character 7 indicates a rather inconspicuous circular protuberant ornamental portion.

I claim:

The ornamental design for a shade bowl, substantially as shown and described.

Signed by me at Steubenville, Jefferson county, Ohio, this 28th day of January, 1918.

JOHN BEISWANGER.
